UNITED STATES PATENT OFFICE

154,621

DESIGN FOR A SUN SKIRT

Naomi Owen Morgan, New York, N. Y.

Application May 20, 1948, Serial No. 146,479

Term of patent 14 years

(Cl. D3—26)

To all whom it may concern:

Be it known that I, Naomi Owen Morgan, a citizen of the United States, residing in the Borough of Manhattan, city, county, and State of New York, have invented a new, original, and ornamental Design for a Sun Skirt, of which the following is a specification, reference being had to the accompanying drawing, forming part thereof.

On the drawings,

Fig. 1 is a front elevational view of a sun skirt embodying my new design, showing the form it takes when draped on the body of the wearer;

Fig. 2 is a rear elevational view of the sun skirt shown in Fig. 1;

Figs. 3 and 4 are views similar, respectively, to Figs. 1 and 2, showing the form the sun skirt takes when draped upon the body of the wearer to cover the bust, but without extension over the shoulder;

Fig. 5 is a rear elevational view, to reduced

scale, showing the sun skirt in the form it takes when not draped on the body of a wearer; and

Fig. 6 is a front elevational view of the undraped skirt form of Fig. 5.

I claim:

The ornamental design for a sun skirt, substantially as shown and described.

NAOMI OWEN MORGAN.
